[57] **CLAIM**

The ornamental design for a golf club having a collapsible shaft, as shown and described.

DESCRIPTION

FIG. 1 is a perspective view of a golf club having a collapsible shaft showing my new design;

FIG. 2 is an exploded left side elevational view thereof;

FIG. 3 is a left side elevational view of FIG. 2;

FIG. 4 is a bottom plan view of FIG. 1;

FIG. 5 is a top plan view of FIG. 1;

FIG. 6 is an enlarged left side elevational view of the golf club head, shown for ease of illustration;

FIG. 7 is an enlarged cross sectional view taken on line 7—7 of FIG. 3;

FIG. 8 is a left side elevational of FIG. 1, the undisclosed opposite side being a mirror image;

FIG. 9 is a front elevational view of FIG. 1;

FIG. 10 is a rear elevational view of FIG. 1;

FIG. 11 is an enlarged top plan view of the shaft receiving chamber of the golf club head, shown for clarity of illustration;

FIG. 12 is a top plan view of the shaft, shown for clarity of illustration; and,

FIG. 13 is a top plan view of FIG. 6.
